UNITED STATES PATENT OFFICE.

ELI J. BUSHEY, OF NEW YORK, N. Y.

MIXER.

1,199,243.

Specification of Letters Patent. Patented Sept. 26, 1916.

Application filed July 30, 1913, Serial No. 782,089. Renewed March 1, 1916. Serial No. 81,552.

To all whom it may concern:

Be it known that I, ELI J. BUSHEY, a citizen of the United States, and a resident of New York, county and State of New York, have invented certain new and useful Improvements in Mixers, of which the following is a full, clear, and exact description.

This invention relates more particularly to a simple device for breaking up and thoroughly mixing the gases for explosive engines.

One of the principal objects of the invention is to provide a simple and efficient device which may be so located between the carbureter and the engine that the explosive mixture from the carbureter is caused to come into contact with and to pass through the device and in its passage thoroughly broken up and given a whirling motion in order that the air and gas or explosive mixture may be thoroughly commingled.

Another object of the invention is to provide a device which may be readily and easily made from an ordinary perforated metal plate and thus provide a device which is not only effective in use but which is inexpensive to manufacture.

A further object of the invention is to provide a simple and efficient device whereby by a comparatively large percentage of kerosene may be mixed with the gasoline and still make the motor more flexible than heretofore.

A still further object of the invention is to provide a device in which any globules of fluid passing with the explosive mixture will be collected by a part of the device and caused to vaporize and to be thoroughly mixed with the explosive mixture as it passes from the carbureter to the engine.

With these and other objects in view, the invention will be hereinafter more particularly described with reference to the accompanying drawings, which form a part of this specification, and will then be pointed out in the claims at the end of the description.

In the drawings, Figure 1 is a vertical section showing one application of a device embodying my invention, the section through the device being taken on the line 1—1 of Fig. 3. Fig. 2 is a detail perspective view of the device. Fig. 3 is a detail plan view; and Fig. 4 is a transverse section taken on the line 4—4 of Fig. 3.

The carbureter 10 and the manifold or in-

take 11 are each provided with flanges 12 opposed to each other. These flanges may be held by bolts 13 or otherwise, and between the flanges may be arranged a packing of any suitable kind to prevent leakage. The parts as thus described, may of the usual or of any preferred construction.

A device 14 corresponding in shape substantially to the shape of the flanges 12 is located between the flanges and has bolt holes 15 for the passage of the bolts 13 in order that the device may be clamped between said flanges 12. The device 14 has a plate-like body 16 and is cut away substantially centrally thereof to provide an opening 16^a. Integral with the body 16 are blades 17 substantially centrally arranged and projecting upward within the manifold 11 and across the opening 16^a to partly close the same. These blades are so formed that they will have substantially the action of propeller blades so that as the gases pass from the carbureter to the engine they will come into contact with the device 14 and by means of the blades will be given a whirling action in order to thoroughly mix the gases.

The blades 17 are formed at the same time that the opening 16^a is formed and in this way only a small part of the material is wasted. The opening 16^a forms spaces around and about the blades 17 for the passage of the explosive mixture and both blades and the body 16 are provided with a number of small openings or apertures 18 to form a perforated device, or the said device may be made from the usual perforated plate or sheet metal which may be purchased in the open market.

It will be evident that as the gas and air or the mixture from the carbureter or other source of supply comes into contact with the blades 17, the mixture will be divided and given a whirling action. The mixture will be further divided by reason of the openings 18 and the device is so constructed that any globules or any fluid matter passing with the gas will be collected on the device and vaporized and the vaporized particles thoroughly mixed with the gases as they pass to the engine. It will be evident also that by the nature of the device, a fluid as kerosene may be mixed with the gasoline and a very effective explosive mixture provided.

It will be understood that while two blades are shown, one or more may be uti-

lized and these blades may be variously shaped, and only the blades may be perforated if desired.

From the foregoing, it will be manifest that a simple and efficient device is provided which is inexpensive to manufacture; that said device may be variously located and utilized for various purposes; that said device is effective in use to vaporize and to 10 thoroughly mix the gases; and that said device may be placed in position without changing the construction of any of the usual parts in connection with which the device is used.

Having thus described my invention, I claim as new and desire to secure by Letters Patent:—

1. A device of the character described, comprising a body, and integral blades extending upwardly and inwardly from said body, said blades and body being of perforated metal.

2. A device of the character described, comprising a plate-like body, and integral perforated blades extending from said body.

3. A device of the character described, comprising a perforated plate-like body, and a blade extending upwardly and inwardly from said body.

4. A device having a plate-like body adapted to be arranged between the carbureter and the engine and having a relatively large opening therethrough, and blades extending from said body across said opening and upwardly therefrom, the

whole device being provided with a large number of small openings.

5. A device having a body adapted to be arranged between the carbureter and the engine and having a relatively large opening therethrough, and integral perforated blades extending across said opening and upwardly therefrom.

6. A device having a plate-like body adapted to be arranged between the carbureter and the engine and having an opening therethrough, and a perforated blade extending across said opening.

7. A device of the character described comprising a plate like body having a relatively large opening therethrough and integral blades extending inwardly across said opening from opposite sides thereof and out of the plane of the plate like body, the inner ends of the blades being disconnected from each other.

8. A device of the character described comprising a plate like body having a relatively large opening therethrough, and integral blades extending from opposite sides of said opening and inwardly past each other and out of the plane of the plate like body.

This specification signed and witnessed this 25th day of July, A. D. 1913.

ELI J. BUSHEY.
